BUILDING UNIT

Franz Wiesinger, Winnipeg, Manitoba, Canada, assignor
to Northwest Design & Fabrication Ltd., Transcona,
Manitoba, Canada

Filed June 14, 1965, Ser. No. 85,711

Term of patent 14 years

(Cl. D13—1)

FIGURE 1 is a top plan view of the building unit.

FIGURE 2 is a front elevation thereof.

FIGURE 3 is a section along the line 3—3 of FIGURE 2.

The rear view of the building is similar in configuration to the front view of the building but is reduced in size.

I claim:

The ornamental design for a building unit, as shown and described.
